UNITED STATES PATENT OFFICE.

EDWARD JAMES DUFF, OF GLASGOW, SCOTLAND.

STEAM-BOILER AND ITS FURNACE.

SPECIFICATION forming part of Letters Patent No. 439,814, dated November 4, 1890.

Application filed May 20, 1890. Serial No. 352,485. (No model.)

To all whom it may concern:

Be it known that I, EDWARD JAMES DUFF, a subject of the Queen of Great Britain and Ireland, and a resident of Glasgow, in the county of Lanark, Scotland, have invented certain new and useful Improvements in Steam-Boilers and their Furnaces, (for which a British patent has been applied for, No. 5,487, April 11, 1890,) of which the following is a specification.

10 This invention has for its object to obtain increased efficiency with absence of smoke in connection with steam-boilers and their furnaces.

The invention is applicable to various kinds 15 of steam-boilers. It is, however, shown on an accompanying sheet of explanatory drawings as applied to a common type of land-boiler, comprising a horizontal cylindrical shell, with two furnaces in flues extending from end to 20 end of the boiler.

Figure 1 is a front end elevation, but with fire-doors and some other parts removed; and Figs. 2 and 3 are longitudinal vertical and horizontal sections.

25 In the drawings the same reference-numerals are used to mark the same or like parts wherever they are repeated.

The grate of each furnace of the boiler consists of a series of longitudinal tubes 5, of 30 steel or other suitable metal, these tubes being inclined so as to be higher at their inner ends and being fixed in outer and inner end castings 6 7 of steel or iron. Access to the grate-tubes 5 for cleaning out or withdrawing 35 them is given through apertures in the end castings 6 7 at the sides opposite to the ends of the tubes, those of the inner end casting 7 being closed by screw-plugs 8, while those of the outer or front end casting 6 are closed by 40 caps 9, (not shown in Fig. 1,) fixed by bolts securing them to internal cross-pieces. Either the screw-plugs 8 or the caps 9 may be used for both end castings 6 7. Each inner end casting 7 is connected by a central vertical 45 pipe 10 to the interior of the boiler through the top of the flue-tube 11, and a hanging or depending bridge or wall 12 of fire-brick (not shown in Fig. 1) is fixed across the upper part of the flue-tube. The outer or front 50 end castings 6 of the two furnaces are connected to curved branches 13 of a pipe 14,

communicating through the front end plate 15 of the boiler with the interior. The branch pipes 13 are provided with downward continuations 16, which are fitted with stop-cocks 55 (not shown) and are to be used for blowing off, so as to wash out the grate-tubes 5 whenever it may be thought desirable. The arrangement of the pipes 13 14 is such as to allow of slight movements of the parts of the 60 grate, which may be caused by variations of temperature without any part being injuriously strained. In consequence of the front and back ends of the grate-tubes 5 being connected, respectively, to lower and higher parts 65 of the interior of the boiler, a vigorous circulation of the water takes place through the grate-tubes toward their inner ends, and this circulation is further promoted by the inclination of the grate-tubes. 70

Beneath the grate-tubes 5 there is in each case a transverse partition 17, and in the space 18 from this partition to the front end of the grate-tubes air passes up between the grate-tubes and through the fuel lying upon 75 them; but in the space 19, at the inner side of the partition 17, the gases pass downward between the grate-tubes, and thence onward along the flue. The fuel is placed on the grate-tubes 5, so as to extend from their front ends 80 inward beyond the partition 17, but not close up to the hanging bridge 12, a division consisting of a fire-brick bar 20 being placed across the grate-tubes 5, so as to keep a space 85 21 at their inner ends clear of fuel and so that a portion of the gases may pass downward between them without being obstructed by the fuel. With the arrangements which have been described the gases from the fuel at the outer part of the furnace are compelled 90 to take a downward course at the inner part, partly through some fuel, but chiefly through the space 21 at the inner ends of the grate-tubes, and in consequence of this downward course of the fuel gases they pass in close contact with the incandescent fuel at the inner part of the furnace, and their combustible constituents are thoroughly ignited and the production of smoke prevented. By providing 95 the comparatively free space 21 at the extreme 100 inner end of the furnace for the downward passage of a portion of the fuel gases there is

avoided the great resistance to the flow of the gases, which has been the cause of inefficiency in attempts to make the whole of the fuel gases pass downward through fuel.

5 The transverse partition 17 beneath the grate tubes 5, between the spaces 18 19, is provided with a door 22, through which ashes may be withdrawn, and if found advantageous a regulated supply of air may be admitted through the partition. Ordinary fire-doors 23 (not shown in Fig. 1) are fitted at the frontends of the furnaces above the grate-tubes 5, and air may be admitted through regulated openings in these doors.

15 The apparatus may be modified by arranging the space 21 at the inner end of the furnace for the free passage of a portion of the fire gases beyond the extreme ends of the grate-tubes 5, and in that case the said space, 20 having no tubes across it, may be reduced in size.

The air may be supplied by ordinary draft or by what is known as "forced draft."

What I claim as my invention, is—

In a steam-boiler furnace having a water-tube grate in communication at its opposite ends with the boiler, a hanging bridge or partition closing the inner end of the space above the grate, a partition separating an outer part of the space under the grate from an inner part communicating with the continuation of the flue, and a division leaving a space at the inner end of the grate for the free passage of a portion of the fire gases, all in combination and arranged substantially as and for 35 the purposes hereinbefore described.

In testimony whereof I have signed my name to this specification in the presence of two subscribing witnesses.

EDWARD JAMES DUFF.
